UNITED STATES PATENT OFFICE

KING WILLIAM GILLESPIE, OF LINCOLN, NEBRASKA.

BODY-HOIST.

1,277,907

Specification of Letters Patent. Patented Sept. 3, 1918.

Application filed April 10, 1918. Serial No. 227,693.

To all whom it may concern:

Be it known that I, KING W. GILLESPIE, a citizen of the United States, and a resident of Lincoln, in the county of Lancaster and State of Nebraska, have made certain new and useful Improvements in Body-Hoists, of which the following is a specification.

My present invention relates generally to hoists and more particularly to hoists for the bodies of dumping wagons, my object being the provision of a generally improved structure, the operating parts of which follow the movement of the wagon body, provide for more effective operation, and combine to form a simple economical structure which will at the same time be strong and durable in use.

With these general objects in mind the further objects and their resulting advantages will be better understood by reference to the following detailed description, referring to the accompanying drawings forming a part of this specification, and wherein:

Fig. 1 is a perspective view illustrating the practical application of my invention;

Fig. 2 is a front elevation of my invention;

Fig. 3 is a vertical section taken substantially on line 3--3 of Fig. 2 and enlarged;

Fig. 4 is a detailed vertical section taken through a portion of the gearing substantially on line 4--4 of Fig. 2;

Fig. 5 is a detailed perspective view of the main portion of the hoist frame removed;

Fig. 6 is a detailed perspective view illustrating the engaged relation of the body carried roller with the hoist carried track;

Fig. 7 is a detail vertical section taken substantially on line 7--7 of Fig. 6, and,

Fig. 8 is a detailed perspective view of the two parts of the sheave support of the hoist body.

Referring now to these figures, and particularly to Fig. 1, my invention is designed for use in connection with the bodies of dumping wagons, and, for location between the driver's seat and the front end of a wagon body such as for instance indicated at A in the said figure, the body being pivoted at its rear end to the running gear or chassis, portions of which are seen at B by hinges or other suitable pivots.

My invention is designed to be interposed between the front end of the body A and the

driver's seat or like for structure, and to this end is intended to occupy but a minimum space and still operate readily and quickly for the intended purpose.

For the purpose of my invention, a cross piece 10 is secured transversely of the running gear or chassis B in any suitable manner, and provided at spaced points with brackets 11, in which the depending spaced feet 12 of the main portion of the hoist frame are pivoted by transversely extending pivots 13 which thus enable the hoist frame to swing forwardly and inwardly of the running gear or chassis B, in order to adapt itself to the arc of movement of the front end of the body A.

The frame of the hoist includes an upper sheave support 14, an intermediate tubular upright 15, and an annular inverted U-shaped frame 16, the latter of which is preferably semi-tubular in form with a lower transverse cross piece 17 and a rigid upright 18 intermediate its side portions, which upright 18 and one of the side portions of the said frame have openings 19 and 20, aligned with one another, so as to form bearings for a plurality of shafts 21--22 and 23.

At its upper curved portion the inverted U frame 16 has a semi-tubular extension 24 projecting therefrom in a direction parallel to its longitudinal axis for the reception of the lower end of the tubular upright 15, which latter is securely fastened by machine screws and the like 25.

The sheave support 14 shown in detail in Fig. 8 includes two side uprights 26 and 27 having apertures 28 receiving the side trunnions, or ends of the shaft of the sheave 29 over which the hoisting cable 30 passes. At their extreme upper ends these side portions 26 and 27 of the sheave support have curved extensions 31 which meet above the space between the uprights so as to close the latter and prevent accidental displacement of the hoisting cable, these extensions having relatively engaging lugs and recesses 32 and 33 so as to avoid any tendency of lateral displacement. The lower portions of the uprights 26 and 27 are flanged as at 34 in Fig. 105, and provided with depending semi-tubular extensions 35 which when together are adapted to interfit the tubular end of the upright 15 in the main frame, said extensions 35 having internal bosses 36, one of which has an end recess to receive the end of the other so that the two extensions may

be temporarily held in proper relative position as they are moved in connected relation into the upper end of the upright 15 within which they are firmly held by shrinking or brazing or in any other suitable manner.

Vertically along the upright 15 and projecting rearwardly therefrom at one side of the vertical plane of its longitudinal axis 10 is an upright track 37 having lateral extensions 38 and 39 adjacent its upper and lower ends, which are bolted or otherwise secured through openings 40 to the tubular upright 15, the lower end of this track 37 having 15 laterally projecting pins 41, the purpose of which will be presently described.

In utilizing my invention, a bracket 42 is provided upon the lower portion of the forward end of the body A, said bracket having 20 a bifurcated arm 43 curved forwardly from its upper portion and having a roller 44 mounted in the bifurcation and this arm has bifurcated portions which are adapted to straddle the track 37 so that the roller 44 25 is thus engageable with the rear edge of the track 37.

As seen in Fig. 6 in particular, the bifurcated portions of the arm 43 have recesses which receive the laterally projecting pins 30 41 of the track in the lowermost position of the body A, so as to entirely steady the hoisting apparatus and prevent the same from swinging movement on its lower pivots 18 and rattling against the body.

35 It is obvious that the body A moves up and down, its arc of movement is compensated for by the lower pivots 18 of the hoist frame, so that the roller 44 will remain in engagement with the rear edge of the vertical track 37 at all times.

One end of the hoisting cable 30 is secured beneath the body A in any suitable manner, and passes upwardly around the lower forward wear plate 45 of the body, 45 and downwardly around the sheave 29, its opposite end being secured to the drum 46 mounted upon the upper shaft 23 and in connection with a gear wheel 47. This gear wheel is in mesh with a gear wheel 48 upon 50 the intermediate shaft 22 in connection with a gear 49 in mesh with a gear 50 upon the lower shaft 21. The lower shaft 21 is laterally extended beyond one side of the lower U-frame 16, and is squared to receive a crank 55 51, rotation of which serves to rotate the drum through the series of gears 47-48-49 and 50, so as to wind the cable 30 upon the drum and elevate the front end of the body A.

60 The lower cross piece 17 of the U-shaped frame 16 has a lateral supporting arm 51 secured thereto for supporting a pivoted dog engageable with the lower gear 50 in the

manner shown in Fig. 14, the dog 52 being secured to one end of a controlling rod 53 passing through the supporting arm 51, and laterally beyond one side of the U-frame 16 with a terminal handle 54 adjacent to the crank 51, so that the dog 52 may be conveniently moved into and out of active position. In this way it is obvious that when the body A has been elevated as above described the dog 52 utilized to hold the body in elevated position while dumping may be released and the body A thus permitted to lower of its own weight, either after removing the crank 51 from connection with the squared end of the shaft 21 or under control of this crank in the position shown.

It is obvious from the foregoing that my invention provides a body hoist which will be simple, comparatively inexpensive, strong and durable, as well as one which will occupy a minimum space, permit of ready and quick operations, and avoid all danger of the lateral displacement of the parts or rattling thereof in use.

I claim:—

1. A hoist of the character described including a lower inverted U-shaped frame having depending pivotally mounted feet at the sides thereof, and provided with an upper extension, a tubular upright interfitting the said upper extension and secured thereto, a sheave support having extensions interfitting the upper end of the tubular upright, a sheave mounted within said sheave support, a hoisting connection extending over the sheave, and a winding device for the hoisting connection mounted within the lower U-frame, as described.

2. In a body hoist, the combination with a body vertically movable at its forward end and having a bracket provided with a bifurcated arm, a roller mounted within the bifurcation of the arm, a hoisting frame pivotally mounted adjacent the forward end of the wagon body and having an upright track engaged by the body roller, and which the bifurcated portions of the body arm straddle, a hoisting mechanism carried by the hoisting frame and including a flexible connection secured at one end of the body, said track having lateral projections adjacent its lower end and said bifurcated portions of said body arm having recesses receiving the projections of the track in the normal lower position of the body to hold the hoisting frame immovable and prevent rattling thereof.

KING WILLIAM GILLESPIE.
